UNITED STATES PATENT OFFICE.

STEPHEN A. DOBYNE, OF ST. LOUIS, MISSOURI, ASSIGNOR TO CHAMPION SHOE MANUFACTURING COMPANY, OF ST. LOUIS, MISSOURI, A CORPORATION OF MISSOURI.

FASTENER- STOCK-SUPPLYING MECHANISM FOR FASTENER-INSERTING MACHINES.

Application filed July 19, 1918. Serial No. 245,731.

To all whom it may concern:

Be it known that I, STEPHEN A. DOBYNE, a citizen of the United States, and residing at St. Louis, Missouri, have invented the
5 new and useful Improvement in Fastener-Stock-Supplying Mechanism for Fastener-Inserting Machines, of which the following is a specification.

This invention relates to fastener inserting machines, and more particularly to fastener stock supporting mechanism for such machines.

In fastener inserting machines, such, for instance, as shown and described in my application Serial No. 245,730, filed of even date herewith, a guide is provided for feeding a series of strands of fastener stock, in the form of connected fasteners or slugs. The fastener stock is cut by suitable mechanism, and driven into the work, such as the sole or heel of a shoe. The fastener stock is wound on reels and this stock is unreeled and led to the fastener guiding and inserting mechanism. Since the fastener stock is, however, unusually heavy, difficulties are experienced in taking out the kinks and straightening the strands.

One of the objects of this invention, therefore, is to provide a fastener inserting machine, in which the fastener stock reels are so supported as to provide long strands of fastener stock between the reels and the fastener inserting mechanism, in order to straighten the fastener stock and take the kinks out of the same.

Another object is to provide a reel support which will support one or more reels in such a manner as to permit quick removal and replacement of a reel, and which will support the reel in such a manner as to provide for a uniform feed of the fastener stock strands.

Another object is to improve the mechanism in detail of construction, to provide simple and reliable mechanism and which is economical to manufacture.

Further objects will appear from the detail description taken in connection with the accompanying drawings, in which:

50 Figure 1 is a front elevation of a fastener inserting machine showing the fastener stock supporting mechanism embodied in this invention;

Figure 2 is a detail plan view of the reel support and its reels;

Figure 3 is a section on the line 3-3
Figure 2;

Figure 4 is a section on the line 4-4, Figure 3;

Figures 5 and 6 are perspective views of 60 the two parts of a reel;

Figure 7 is a detail side elevation of the directing or guiding means for the strands of fastener stock; and,

Figure 8 is a section on the line 8—8, 65
Figure 7.

Referring to the accompanying drawings, 1 designates a machine column or frame which has mounted thereon a machine head 2 carrying the fastener inserting mechanism. 70 This fastener inserting mechanism may be of the construction shown and described in my application referred to, and comprises, generally stated, a throat 3, a fastener stock guide 4 adapted to guide a series of strands of fastener stock to the throat, a feeding and cutting member 5 for cutting off a fastener or slug from the selected strand of fastener stock and a driver 6 for driving the fasteners or slugs, all of these parts being operated by the main drive shaft 7 as described in my application referred to. 75 80

The machine column has mounted thereon, a shaft 10 supporting the frame 11 of the reel support. For this purpose, this frame is provided with a hub 12 engaging the end of the shaft, and this hub is provided with a set-screw 13 for removably securing the frame in position. This frame is provided, as shown in Figures 2, 3 and 4 with a series of bearings 14 for receiving the shafts 15 of the reels, the reels being spaced by cross pieces 16 in which the bearings are formed, and these bearings are half round so as to permit ready removement or replacement of the reels. Referring now to Figures 2 to 6 inclusive, the reel comprises a pair of plates 17 and 18, each formed preferably of cast metal, and having lugs 19 and 20 and 21 which interlock to form sup-

and 20 and 21 which interlock to form supports for the strands of fastener stock which, as shown in Figure 3, may be a series of connected headed fasteners A, or as shown in Figure 7, a series of connected slugs B. The lugs 21 on the end plate 18 are connected by a cross piece 22 cooperated with and engaging with the cross piece 23 on the plate 17. The cross piece 22 has a hub 24 which is bored to receive the shaft or pintle 15 and which is received in the 110

opening 25 of the cross piece 23. The cross piece 22 has formed thereon or attached thereto, bosses 26, each of which receives the head 27 of a pin 28 which slides in the 5 boss and through the plate, and is provided at its end with another head 29 adapted to pass through a slot 30 in the cross piece 23. Each boss receives a spring 31 arranged on the pin 28 and bearing against the head 27.

10 In assembling the reel, the heads 29 are placed in position, as shown in Figure 5, so as to pass through the slots 30 and the heads 29 are then forced out and given a quarter of a turn so as to lock them in position, as shown in Figure 4. In order to 15 retain the heads in position, the cross piece 23 has struck up therefrom, lugs 32 which engage opposite sides of the head 29 to retain it in locked position. It will, therefore, 20 be seen that this reel can be readily removed from the frame, the parts thereof separated, and the coil of fastener stock can then be readily placed on the reel and the reel assembled and replaced in its frame.

25 Referring now to Figures 2 to 4 inclusive, mounted in a pair of lugs 35 is a shaft 36, which has mounted thereon a series of arms 37, each of which in turn has mounted loosely thereon, a weighted head 38 which 30 has a leather or other form of facing 39 adapted to bear on and engage the coiled fastener stock on the reel. These weighted heads 38 bearing on the coiled fastener stock provide means for braking the reels, and 35 therefore preventing overthrow, and also provide means for retaining the fastener stock against uncoiling. When a reel is to be removed, the head can, of course, be readily swung back out of the way.

40 The frame has attached thereto, a case comprising a section 40 fixed to the frame and a section 41 is provided with bearing lugs 42 to permit this cover section to be 45 movably supported on the shaft 36. This cover section is provided with slots 43 permitting the fastener stock to pass therethrough and the cover is also provided with a handle 44 to permit the manipulation of the cover.

50 The fastener stock passes from the reel to suitable guiding and straightening mechanism. For this purpose, the machine has mounted thereon a bracket 50, Figures 1, 7, and 8, which is provided with a shaft 51 55 supporting a series of guiding and straightening rolls 52. Each of these guiding and straightening rolls is grooved, the groove consisting of a deep straight section 53, and a beveled section 54. Cooperating with 60 these grooves are a series of flanged rolls 55 mounted on a shaft 56 on the bracket 50. Upon reference to Figure 8, it will be noted that the lowermost roll 52 has a deeper section 53 than the other rolls, while the roll 55 has a deeper flanged section. These co-

operating rolls receive the slug stock, which is of less width than the fastener stock, and therefore requires more positive means for guiding and directing it to the fastener stock guide 4.

It will be noted that the fastener stock reel support is mounted below the fastener inserting mechanism so as to provide a long strand of fastener stock between the reel and the fastener inserting, guiding and directing means. The provision of such a long strand of fastener stock allows this fastener stock to straighten more readily from its coiled condition and prevents the formation of kinks. It will also be noted that on account of the position of the reel, the fastener stock is given a quarter turn before reaching the directing and straightening rolls, this also necessitates the provision of a long strand in order to prevent twisting of the strand stock. Now, unless the reel support is placed on the machine column or frame below the fastener inserting mechanism, the provision of such a long strand is an impossibility, unless the machine is extraordinarily high or wide. The positioning of the reel support in the manner described maintains to the machine staple. As the fastener strands pass between the rolls 52 and 55, the fastener stock will be convolved, directed and delivered to the fastener stock guide 4 in ideal condition to be formed into fasteners or slugs and driven.

It is obvious that various changes may be made in the details of construction without departing from the spirit of this invention; and it is to be understood, therefore, that this invention is not to be limited to the specific details shown and described.

Having thus described the invention, what is claimed is:

1. In a string nailing machine having a guide for a string of connected nails, means for feeding and cutting the string, means for inserting the nails, a source of nail string supply, and means arranged between said source of supply and said guide, constructed and arranged to twist the nail string to correct relation to said guide.

2. In a string nailing machine having a guide for a string of connected nails, means for feeding and cutting the string, means for inserting the nails, a source of nail string supply, and means arranged between said source of supply and said guide and having a groove receiving the nail string, constructed and arranged to twist the nail string to correct relation to said guide.

3. In a string nailing machine having a guide for a string of connected nails, means for feeding and cutting the string, means for inserting the nails, a source of nail string supply, and a pair of cooperating rolls arranged between said source of sup-

ply and said guide, constructed and arranged to twist the nail string to correct relation to said guide.

4. In a string nailing machine having a guide for a string of connected nails, means for inserting the nails, a plurality of reels for a plurality of nail strings, and means

arranged between the guide and the reels, constructed and arranged to twist the strings into correct relation with said guide. 10

In testimony whereof I affix my signature this 6th day of October, 1917.

STEPHEN A. DOBYNE.
